Pittsburgh, Pa., a corporation of Pennsylvania

Application January 15, 1952, Serial No. 266,569

7 Claims. (Cl. 302—14)

1

The present invention relates to the art of transporting solids suspended in a liquid vehicle.

This application is a continuation-in-part of our copending patent application S. N. 204,628, filed January 5, 1951, and entitled "Transportation of Solids Through Pipelines."

Conventional mechanical pumps in general are unsatisfactory for pumping solids which are suspended in liquids because of the excessive wearing of the moving parts of such pumps occasioned by the solids and also because of the attrition of the solids occasioned by the moving parts of the pump. The present invention is directed to a pumping device which is capable of raising the pressure of solid-liquid suspensions without permitting the solids to contact the moving parts of the pumping equipment. For convenience, we shall hereafter refer to the suspensions of solids in liquids as slurries.

According to this invention, equal volumes of the slurry, hereinafter called "slugs," are introduced alternately into one of two parallel transfer zones, are pressurized therein by means of a high pressure pumping fluid, and are discharged therefrom at an elevated pressure. Pumping fluid is continuously recovered from the transfer zones, is repressurized, and recirculated to raise the pressure of other slugs of slurry.

We have discovered that the operation of such a pumping system is greatly improved by the introduction of a small portion of the pumping liquid between successive slugs of pressurized slurry. This addition of pumping liquid assures that the slurry is completely removed from each pumping stroke. To compensate for the loss of the small portion of pumping liquid during each pumping stroke, a small amount of make-up pumping liquid must be added to the pumping system.

The object of this invention is to provide for pumping slurries without causing excessive wear or attrition on the moving parts of the pumping system or on the transported solids.

Another object of the invention is to provide a system for elevating the pressure of a slurry in a simple manner.

For a further understanding of our invention, its additional objects and advantages, reference should be had to the accompanying description and drawings in which:

Figure 1 is a drawing, partly diagrammatic and partly in cross section, showing the preferred embodiment of a slurry pumping station to which the present invention is applicable; and

Figure 2 shows the apparatus of Figure 1 in a different stage of operation; and

2

Figure 3 is a drawing, partly diagrammatic and partly in cross section, showing another embodiment of pumping station to which the present invention is applicable; and

5 Figure 4 shows the apparatus of Figure 3 in a different stage of operation.

Figures 1 and 2 represent pumping apparatus corresponding to that disclosed in a U. S. patent application Serial No. 266,568 filed on even date 10 herewith, by one of the present inventors and entitled "Transportation of Solids Through Pipelines," and assigned to the assignee of the present application.

Figures 3 and 4 represent pumping apparatus 15 corresponding to that disclosed in U. S. patent application S. N. 204,628, filed January 5, 1951, referred to above.

Referring to Figure 1, a pumping apparatus for pumping a suspension of finely divided coal 20 in water is shown in combination with a slurry transportation pipeline proper which has a low pressure section 30 and a high pressure section 31. Communicating with the low pressure section 30 are two conduits 33 and 34 whose diameter is substantially the same as that of the pipeline proper. Communicating with the high pressure pipeline section are two conduits 37 and 38. Conduits 33 and 37 join and communicate with a transfer pipe 35; conduits 34 and 38 join and 25 communicate with a transfer pipe 36. The transfer pipes 35 and 36 are of equal length and have a diameter substantially the same as that of the pipeline proper.

Check valves 39, 40, 41 and 42 are provided 30 in the conduits 33, 34, 37 and 38 respectively. The check valves 39 and 40 permit fluids to flow only away from the low pressure pipeline section 30; the check valves 41 and 42 permit fluids to flow only toward the high pressure pipeline section 31. The extended terminals of the transfer pipes 35 and 36 join at the diametrically opposite 35 apertures of a four-way valve 43 which is adapted for cyclic operation.

A continuously operating high pressure water pump 46 draws suction from a low pressure water pipe 44 and discharges high pressure water 40 through high pressure pipe 45. The high pressure water line 45 and the low pressure water line 44 communicate with the remaining opposing valve apertures of the four-way valve 43.

According to the present invention, make-up water (pumping fluid) is introduced into the water portion of the pumping system through a conduit 47 which communicates with the low pressure water line 44. A pump 48 is provided 50 for introducing the make-up water and a valve

49 is provided to throttle the make-up water according to the operating conditions existing in the system.

The operation of the pumping system shown in Figures 1 and 2 will be briefly described. 5 For further details relating to this pumping scheme, reference should be had to the above mentioned copending U. S. patent application filed on even date herewith.

A slurry of the finely divided coal and water travels at constant velocity through pipeline section 30 under a low pressure. The four-way valve 43 has been in the position indicated in Figure 1 for almost one complete half-cycle of the pumping apparatus. Throughout this half- 10 cycle, low pressure slurry from the pipeline 35 has been passing through conduit 33, open check valve 39 and into the transfer pipe 35. As shown, the slug of slurry 50 has filled the transfer pipe 35 to a point near the four-way valve 43. The slurry which has been filling the transfer pipe 35 has been displacing water from the transfer pipe 35 through the four-way valve 43 into the low 15 pressure water line 44. The pump 46 has been repressurizing the water from pipe 44 and discharging said water under high pressure through the high pressure water line 45 and the four-way valve 43 into the transfer pipe 35. The slug of slurry 51, which had been introduced into the transfer pipe 35 during the preceding half-cycle of the pumping system, has been displaced by the high pressure water and is discharged under 20 high pressure from the transfer pipe 35 through the conduit 38 and open check valve 42 into the high pressure pipeline section 31 for further transportation.

During the entire half-cycle shown in Figure 1, the pressure in transfer pipe 35 exceeds that in the low pressure slurry pipeline section 30 and 31. Consequently, the check valve 40 is closed and the check valve 42 is open throughout the half-cycle. Similarly the pressure in transfer pipe 35, during the entire half-cycle shown in Figure 1, is less than that in the slurry pipeline 30 and 31. Accordingly, the check valve 41 is closed and the check valve 39 is open throughout the half-cycle.

At the termination of the pumping stroke illustrated by Figure 1, the slurry slug 50 will have advanced in the transfer pipe 35 to a point just short of the four-way valve 43. At this same moment, all of the slurry slug 51 will have been displaced from the transfer pipe 35 past the check valve 42 in the conduit 38 and, in addition, a small slug of clean pressurized water will have followed the slug of slurry 51 through the check valve 38. Thereupon the system will be in condition for switching the four-way valve 43 to the position shown in Figure 2 in order that the other half-cycle may commence. The switching of valve 43 may be effected by any conventional timing device (not shown).

The apparatus of Figure 2 is identical with that shown in Figure 1 except that (a) the valve 43 is in its alternate position, where it remains throughout the half-cycle illustrated by Figure 2, and (b) the check valves are in their alternate position automatically to correspond to the reversed position of the valve 43. As shown in Figure 2, high pressure water enters the transfer pipe 35 from the high pressure water line 45. Water which has been introduced into the transfer pipe 35 during the preceding half-cycle (Figure 1) is withdrawn through the valve 43 to

the low pressure water line 44 for repressurizing and recirculation into transfer pipe 35.

Check valves 39 and 42 are closed; check valves 40 and 41 are open. Slurry from the low pressure pipeline 30 enters the transfer pipe 35 through conduit 34 and the open check valve 40. Pressurized slurry from transfer pipe 35 is displaced under high pressure through conduit 37 and open check valve 41 into the high pressure slurry pipeline 31. The operation continues until the slug of slurry 52 fills the transfer pipe 35 to a point just short of the four-way valve 43. This point corresponds to the point of furthest advance of the slurry slug in the other transfer pipe during the preceding half-cycle. At this precise moment, all of the slurry slug 50 has been discharged from the transfer pipe 35 and a small slug of clear water has followed the slug of slurry through the check valve 41. The valve 43 then is in condition for switching back to the position illustrated in Figure 1. The first half-cycle thereupon is repeated.

Throughout both half-cycles of the pumping system, clear make-up water is continuously 25 added to the low pressure water pipe 44 through conduit 47 to compensate for the small amount of water which is discharged into the pipeline proper following each pumping stroke.

We have found that the addition of a small 30 slug of clear water to the pipeline proper between each slug of slurry increases the useful life of the check valves 41 and 42 by permitting them to be actuated only in clear water. Furthermore, we have found that the controlled use 35 of water slugs prevents the slurry from entering the four-way valve 43. This not only means that the four-way valve thus operates only in clear water and thereby has a maximum useful life, but also slurry is prevented from entering the 40 water pump 46 where any solids could cause great damage to rapidly moving parts of the pump. Unless the small slug of clear water is employed after each slug of slurry is discharged, each successive slurry slug will approach a point in the transfer pipe nearer to the four-way valve 43 than the preceding slug. After a few pumping cycles, the slurry will creep into the valve and thence into the water pumping system. Water slugs and make-up water in accordance with the present invention, prevent this creeping phenomenon.

The method of the present invention will now be described in connection with the apparatus illustrated in Figures 3 and 4. The operation of this apparatus will be briefly described. For further operational details, reference should be had to the above mentioned copending U. S. patent application S. N. 204,628, filed January 5, 1951.

The pumping apparatus is shown in combination 60 with a pipeline which has a low pressure section 60 and a high pressure section 61. Two four-way valves are provided: the low pressure pipeline section communicates with one valve aperture of one valve 62 and the high pressure 65 pipeline section communicates with one aperture of the other valve 63. A high pressure water pump 64 is provided for elevating the pressure of water from low pressure water line 65 and discharging said water under pressure through high pressure water line 66. The high pressure water line 70 communicates with an aperture of the four-way valve 62 opposite from that of the low pressure pipeline 60. The low pressure water line 65 communicates with an aperture of

the four-way valve 63 opposite from that of the high pressure pipeline 61.

Two transfer pipes 67 and 68 are provided with a diameter substantially the same as that of the pipeline proper. These transfer pipes are of the same length and communicate at one end with the two remaining valve apertures of the four-way valve 62. At their other ends, these transfer pipes communicate with the two remaining apertures of the four-way valve 63. A cycle timing device 69 is provided to actuate simultaneously the two four-way valves 62 and 63 at regular predetermined time intervals.

With the valves in the position shown in Figure 3, slurry from the low pressure section of the pipeline 60 enters the transfer pipe 67 through the valve 62. Water from the transfer pipe 67 passes through the valve 63 into the low pressure water line 65. The pump 64 draws its suction from the water pipe 65, pressurizes the water and discharges it into the high pressure water line 66. High pressure water passes through the four-way valve 62 into the transfer pipe 68 where it displaces a previously introduced slug of slurry into the pipeline proper 61 through the valve 63. The half-cycle as illustrated in Figure 3 is almost terminated. The slug of slurry 70 being introduced into the transfer pipe 67 has almost reached the four-way valve 63. Similarly the slug of slurry 71, which was introduced into the transfer pipe 68 during the preceding half-cycle, has been almost fully discharged from the transfer pipe. The valves 62 and 63 will be actuated simultaneously when the slug of slurry 70 reaches a predetermined point in the transfer pipe 67, just short of the valve 63. At this same moment, the entire slug of slurry 71 will have passed through the valve 63 and also a small amount of additional clear water will have followed the slug of slurry through the valve 63. When the valves are switched accordingly, they will assume the positions shown in Figure 4. Thus, Figure 4 illustrates the conditions prevailing throughout the other half-cycle of the pumping system. The slurry is shown at a point about midway through the second half-cycle.

During the half-cycle of Figure 4, slurry from pipeline 60 is introduced into the transfer pipe 68 through the four-way valve 62. Water from the transfer pipe 68 passes through the four-way valve 63 into the low pressure water line 65 to the pump 64 where it is pressurized and discharged into the high pressure water line 66. The high pressure water passes through the four-way valve 62 into the transfer pipe 67 where it pressurizes the slug of slurry therein. The slug of slurry 70 is discharged under pressure into the pipeline proper 61. The half-cycle of Figure 4 continues until the newly introduced slug of slurry 71 reaches a point just short of the four-way valve 63. At the same moment, the entire slug of slurry 70 has passed through the valve 63 and has been followed by a small slug of clear water. Thereupon the valves are switched back to the position shown in Figure 3 and the first half-cycle is repeated.

To compensate the recirculating water system for the small slugs of water which are discharged following each slug of slurry, a make-up water system is provided. Clear make-up water is introduced from conduit 72 into the low pressure water line 65 continuously under the control of a valve 73. A pump 74 is provided in conduit 72 to furnish the necessary pressure.

The valve switching operation in this modification of the pumping apparatus is accomplished by means of some form of automatic timing device 69 which is regulated to actuate the valve switching mechanism at regular predetermined time intervals. The predetermined time is that time required for a slug of slurry to substantially fill one of the transfer pipes as above described. This time, of course, is a function of the linear velocity of the slurry in the pipeline proper.

Also in the pumping apparatus of Figures 3 and 4, we have discovered that the addition of a small slug of clear water to the discharge pipeline is necessary in order to assure that the four-way valve 63 operates only in clear water, thereby reducing the attrition of the valve parts from the solids in the slurry. Moreover, unless a small slug of clear water is employed following each slug of slurry, some solid particles will remain in the transfer pipes after the four-way valves have been switched. These solids thereupon would be directed into the low pressure water line 65 and thence into the pump 64, thereby reducing the useful life of the pump. However, if the entire transfer pipe and valve 63 are flushed out by means of an additional small slug of clear water in accordance with the present invention, these difficulties are avoided.

The two pumping systems described herein for transporting slurries include the common steps of removing equal slugs of slurry from a pipeline, transferring these slugs to a transfer zone, pressurizing the slugs of slurry by means of a high pressure liquid, displacing the slugs of slurry back into the pipeline by means of the high pressure liquid, introducing small slugs of the clear liquid into the pipeline following each slug of slurry, recovering the pumping liquid, repressurizing the pumping liquid and recycling the pumping liquid for further use as a pressurizing medium. In order to compensate for the introduction of small amounts of clear liquid into the discharge pipeline after each slurry slug, it is necessary that the supply of pumping water be augmented by furnishing clear make-up liquid into the system through the low pressure portion of the recirculating liquid pumping system.

Although the present specification presents only two modifications of pumping systems to which the present invention is applicable, nevertheless it is comprehended that the present invention be applied to any system for pumping solids in a liquid vehicle in which the pumping impetus is supplied by means of an independent recirculating liquid medium. For example, the two copending patent applications referred to above disclose various modifications of pumping schemes to which the present invention is applicable.

It should be pointed out that the pumping systems of the above mentioned two copending applications are limited to systems in which the transfer zones are of substantially the same diameter as the pipeline proper. The purpose of this limitation is to maintain a substantially constant velocity of the slurries through the transfer zones to minimize the settling tendencies of the solids. However, the present invention is comprehended in a broader form and is applicable even to systems in which the solids settling tendency is not a factor. Thus, the present invention is intended to pertain to recirculating liquid pumping systems in which the transfer zones have diameters which differ from that of the pipeline proper. For example, the transfer zones

could be tanks. It should also be emphasized that the pumping fluid need not be the same liquid as that used in the slurry.

According to the provisions of the patent statutes, we have explained the principle, preferred embodiment and mode of operation of our invention and have illustrated and described what we now consider to represent its best embodiment. However, we desire to have it understood that, within the scope of the appended claims, the invention may be practiced otherwise than as specifically illustrated and described.

We claim:

1. In a method for pumping slurries in a pumping system which employs a recirculating pumping liquid to pressurize slugs of slurry, the improvement which comprises the steps of discharging a slug of the pumping liquid directly following each slug of discharged slurry and adding make-up pumping liquid to the recirculating pumping liquid system to compensate for the slugs of pumping liquid which are discharged.

2. A method for pumping slurries through pipes which comprises introducing equal volume slugs of slurry alternately into one of two transfer zones connected in parallel, introducing pressurized pumping liquid into said transfer zone to pressurize said slurry in said transfer zone, discharging said slurry under pressure into a pipeline by displacement with said pumping liquid, adding a slug of said pumping liquid to said pipeline directly following the discharge of said slug of slurry into the said pipeline, recovering the remaining pumping liquid, adding make-up pumping liquid to said recovered pumping liquid, repressurizing said pumping liquid and recirculating the repressurized pumping liquid to one of the said transfer zones.

3. A method for continuously pumping slurries through a pipeline which comprises introducing a slug of slurry into a low pressure transfer zone of two transfer zones connected in parallel, said transfer zones being adapted to function alternately as low pressure zones and high pressure zones, concurrently recovering previously introduced pumping liquid from said low pressure transfer zone, continuously adding make-up

pumping liquid to said recovered pumping liquid, continuously pressurizing said pumping liquid and introducing said pressurized pumping liquid into said high pressure transfer zone to displace therefrom a slug of slurry which has been previously introduced therein, discharging from said high pressure transfer zone in addition to said previously introduced slug of slurry a slug of said pressurized pumping liquid, thereupon diverting a next slug of slurry into the transfer zone containing pumping liquid and diverting said high pressure pumping liquid to the transfer zone containing a slug of slurry to repeat the pumping stroke in a cyclic manner.

15 4. The method of claim 3 in which the slurry and also the pumping liquid pass unidirectionally and sequentially through said transfer zones.

5. The method of claim 3 in which the slurry is introduced into said transfer zones in one direction and is discharged from said transfer zones in the reverse direction.

20 6. The method of claim 3 in which the slurry is a mixture of coal and water and the pumping liquid is water.

25 7. The method of transporting solids through a pipeline which comprises suspending the solids in a subdivided form in a liquid, introducing the resulting suspension into a pipeline, substantially continuously forming discrete slugs of said suspension of predetermined and equal volume, pressurizing each of said slugs by means of a hydraulic liquid, discharging said pressurized slugs and thereafter a portion of said hydraulic liquid, recombining said pressurized slugs and said portions of hydraulic liquid in a continuous sequential stream, and supplying fresh hydraulic fluid in an amount corresponding to that discharged.
